ATTORNEY:

UNITED STATES PATENT OFFICE.

WILLIAM T. SMITH, OF DAYTON, OHIO.

DESIGN FOR A WAGON-BODY.

SPECIFICATION forming part of Design No. 27,352, dated July 13, 1897.

Application filed March 20, 1897. Serial No. 628,529. Term of patent 7 years.

To all whom it may concern:

Be it known that I, WILLIAM T. SMITH, a citizen of the United States, residing at Dayton, in the county of Montgomery and State of Ohio, have invented and produced a new and original Design for the Bodies of Fish-Wagons; and I do declare the following to be a full, clear, and exact description of the invention, reference being had to the accompanying drawing, forming a part thereof.

The leading features of my design consist in a wagon-body of oblong-rectangular shape, the sides and ends of which are in the same horizontal plane throughout, the front portion of which is divided by a transverse space or recess, and the rear portion of which is extended so that a major portion of the body is in the rear of the said transverse space or recess.

The drawing represents a perspective view of my newly-designed wagon-body.

In a detailed description of the design, A designates the forward sides of the wagon-body proper, of uniform height, and the upper and lower longitudinal edges of which are in the same horizontal planes.

B designates a transverse space or recess dividing the front portion C of the body into two compartments of equal size. The sides A at each end of the recess B are cut down 30 to a distance above the lower edges thereof as shown in the drawing.

C' designates a prolongation or rearward-extended portion, the sides D and end E of which are of similar height and in the same 35 horizontal plane with the front sides and end, so that the upper and lower longitudinal sides of the body are in the same plane throughout the length of said body. The rear-extended portion C' of said body is divided from the 40 front portion by a transverse wall G and provides an inclosed compartment in the rear end of the body.

I claim—

The design for a wagon-body as herein 45 shown and described.

In testimony whereof I affix my signature in presence of two witnesses.

WILLIAM T. SMITH.
